GUARD FOR CONTAINERS

Isaac D. Sillman and Harry A. Shane,
New York, N. Y.

Application January 12, 1940, Serial No. 313,470

4 Claims. (Cl. 232—42)

This invention relates to protective devices, particularly for the purpose of preventing the unauthorized removal of milk and other articles which are placed at the doors of dwellings.

It is customary, particularly in the delivery of milk, cream and juices for the bottles or containers to be placed at the doors or windows of stores, apartments and dwelling houses. It often happens that unauthorized individuals remove one or more of such articles and it is difficult to trace such unauthorized removal. Therefore, the present invention is intended and adapted to provide a device which will prevent such removal.

In practicing the present invention, there is provided a locking member which is associated with the door at which the containers or bottles are placed. The device has associated with it a means for clamping over or around the milk container and by a latching or locking means it is held in place until such time as authorized removal is possible. Due to the association of the device with the door and door frame, it is impossible to remove the container and contents after the device has been locked thereon without first opening the door. Thereby, only those persons who have access to the dwelling place are able to remove such containers.

In the accompanying drawing constituting a part hereof, and in which like reference characters indicate like parts.

Fig. 1 is a fragmentary, elevational view of a door and frame showing the device in place and locking a milk container;

Fig. 2 is a side elevational view of the lock itself, some parts being broken away for clearness and showing the device in locked position;

Fig. 3 is a view similar to Fig. 2 showing the lock in inoperative or open position;

Fig. 4 is a front view of said lock;

Fig. 5 is a plan view of the lock and its associated parts;

Fig. 6 is a horizontal, cross-sectional view taken along the line 6—6 of Fig. 4; and

Fig. 7 is a plan view of the guard latch.

The usual door frame or jamb 1 has a door 2 fitted within the same and hinged to the frame along the line 3. A latching device or lock 4 is attached to the door frame at the hinged edge of the door and has pivoted therein a rod 5 at the end of which is carried a cap or cover or container holder 6 which is rectangular in cross-section and is adapted to fit over a container 7 of milk or the like, said container being of similar shape and size so that the cover 6 will fit over a substantial portion thereof. Into the jamb

of the door there is fitted an angular member 8 which is held therein by screws 9 or the like. The lock 4 itself consists of a casing having a pair of angular plates 10 and 11, the latter having formed integrally therewith the attaching portion 8. A pair of tubes 12 forming sockets are pressed or otherwise fitted between plates 10 and 11 and serve to hold the same in their proper positions. On the face of plate 11 is a rectangular or similar opening 13 communicating with identical key-hole slots 14 and 15 located respectively below and above opening 13. The keeper 16 having a stop member 17 near the forward end, projects through opening 13 so that the latch member 18 extends in a position to be engaged as later described. A spiral or other spring 19 surrounding keeper 16 abuts at one end against plate 10 and at the other end against stop 19' constituting part of said keeper.

20 In the opening 14 is placed guard 20 which is pivoted at point 21 in said opening 14, the notches 21' in the sides of guard 20 loosely fitting into the walls of opening 14 and holding the same in proper position, and has an angular upturned end 22 adapted to engage against stop 17. The pivot point 21 is so arranged that in the normal or inoperative position, as shown in Fig. 3, angular portion 22 is out of engagement, leaving the keeper 16 free to move.

30 The rod 5 has its outer end bent at right angles as shown at 23, said portion being held in pivots 24 of cover 6. The opposite end 23' of rod 5 is similarly bent, as shown at 23, to fit into one or other of tubes 12.

35 As shown in Fig. 1, the device is in locked position and in dotted lines there are shown the same elements just prior to being locked over the container 7. Normally, while the device is in inoperative position, it is desirable that the rod 5 be in a substantially vertical position so as not to interfere with the opening and closing of the door and to facilitate the later locking of the device upon the milk or other container. For this purpose there is provided in plate 11, a pair of 40 slots 25 at the upper end thereof, whereby one end of flat spring 26 may be held in said slots. Said spring has a portion 27 bearing against the inside of plate 11 and is formed with a bowed portion 28 which is intended and adapted to hold the rod 5 in vertical position, as more particularly shown in Fig. 6.

45 A cover 29 fits over the entire device 4 and is secured to plate 11 by means of set screw 30.

50 As will be noted more particularly in Fig. 4, there is an opening 13 for the latch 18, an open-

ing 14 for the guard 20, and a pair of slots 25 for the spring 28. There is provided in addition opening 15 similar to 14, but on the opposite side thereof, and there is also provided a pair of slots 25' similar to slots 25 but positioned oppositely thereof. There is also provided a pair of tubes 12, only the lower of which is utilized for the reception of rod 5 as shown in Fig. 4. The purpose of the additional tube 12, opening 15 and slots 25' is to enable the plate 11 to be used in making an assembly of the entire device whether the door swings in one direction or the other. In other words, since doors are mounted in two different positions, it is necessary to provide a device which may be assembled in such a manner as to be accommodated in one or the other of these positions interchangeably. Therefore, with a single type of plate such as plate 11 the entire assembly is made to accommodate whatever the condition may be.

In the operation of the device the rod 5 with cover 6 is placed in a vertical position as shown in Fig. 6, pushed to the right to pass 28 and the door is locked. When a container of milk is delivered, the container 7 is placed on the floor adjacent to the door and the rod 5 is pulled down until cover 6 fits over container 7. In its movement the rod slips past latch 18 and rests upon guard 20, raising the end 22 to fully lock the keeper in place, as shown in Fig. 2. In this position it is impossible to remove the container 7 even if one has access to the latch 18. In order to remove the container 7, it is necessary to first open the door and then pull rod 5 inwardly, thus removing end 23' from tube or socket 12, allowing angular member 22 to fall in the position shown in Fig. 3 to unlock the device 4. With the rod 5 removed from the lock, the container 7 is readily taken therefrom and the rod and cover may then be replaced in the lock in a vertical position or may be held within the house until such time as it is desired to place it in operative position.

Although the invention has been described specifically with the showing of a single embodiment thereof, it is quite apparent that this embodiment illustrates the principles involved and is not to limit the scope of the invention. For instance, although I have shown a holder in Fig. 1 for a single milk container, it is quite apparent that the cover 6 may be made in multiples and may accommodate two or more containers. It may also be made so as to accommodate containers of different sizes, shapes and materials. Furthermore, the device may be so constructed as to be usable for locking other articles than containers of milk.

The top of cover 6 may have a circular cut-out section 6' to fit over the neck of a bottle or other container. Also, the cover may be of such size and extent as to enclose a plurality of containers stacked one above the other. The whole device may be removable from the frame at will including the member fitting into the jamb of the door or the slide of a window. Said member may be fitted into the strike side of a door as well as the hinge side. The reference in the claims to the positioning of said member is to be considered in its broadest sense as the exact

position thereof may be greatly varied within the spirit of the present invention.

What is claimed is:

1. A guard for articles comprising a rod, a lock, a socket in said lock, one end of said rod being bent at right angles and extending horizontally into said socket, said rod being adapted to extend substantially parallel to and adjacent a door in closed position, a spring pressed keeper in said lock and extending horizontally through one side thereof into the path of said parallel portion of said rod and adapted to hold same in locked position, a guard below said keeper having one portion adapted to contact with said keeper to prevent retraction thereof when the other portion of said guard is contacted by said rod.
2. A guard for articles comprising a rod, a lock, a socket in said lock, one end of said rod being bent at right angles and extending horizontally into said socket, said rod being adapted to extend substantially parallel to and adjacent a door in closed position, a spring pressed keeper in said lock and extending horizontally through one side thereof into the path of said parallel portion of said rod and adapted to hold same in locked position, a guard below said keeper having one portion adapted to contact with said keeper to prevent retraction thereof when the other portion of said guard is contacted by said rod.
3. A guard for articles comprising a rod, a lock, a socket in said lock, one end of said rod being bent at right angles and extending horizontally into said socket, said rod being adapted to extend substantially parallel to and adjacent a door in closed position, a spring pressed keeper in said lock and extending horizontally through one side thereof into the path of said parallel portion of said rod and adapted to hold same in locked position, a guard below said keeper having one portion adapted to contact with said keeper to prevent retraction thereof when the other portion of said guard is contacted by said rod, said rod being removably mounted in said socket and adapted to be detached by movement toward said door when the latter is in open position.
4. A guard for articles comprising a rod, a lock, a socket in said lock, one end of said rod being bent at right angles and extending horizontally into said socket, said rod being adapted to extend substantially parallel to and adjacent a door in closed position, a spring pressed keeper in said lock and extending horizontally through one side thereof into the path of said parallel portion of said rod and adapted to hold same in locked position, a pivoted guard below said keeper having one portion adapted to contact with said keeper to prevent retraction thereof when the other portion of said guard is contacted by said rod, the guard being so pivoted that it is normally held in inoperative position by gravity and in operative position by said rod.
5. A guard for articles comprising a rod, a lock, a pair of spaced parallel plates secured together to provide a casing, a horizontal tube passing through said plates and securing the same together and constituting a socket in said lock, one end of said rod being bent at right angles and extending horizontally into said socket, said rod being adapted to extend substantially parallel to and adjacent a door in closed position, a spring pressed keeper in said lock and extending horizontally through one side thereof into the path of said parallel portion of said rod and adapted to hold same in locked position, a guard below said keeper having one portion adapted to contact with said keeper to prevent retraction thereof when the other portion of said guard is contacted by said rod.
